(57) CLAIM

The ornamental design for a fan, as shown and described.

DESCRIPTION

1. Fan
- 1.1 is a front, right perspective view;
- 1.2 is a front elevation view;
- 1.3 is a rear elevation view;
- 1.4 is a left side elevation view;
- 1.5 is a right side elevation view;
- 1.6 is a top plan view; and
- 1.7 is a bottom plan view.

The broken lines shown in the figures represent unclaimed portions of the fan and form no part of the claimed design.
